M. SHULMAN.

MEANS FOR RECORDING AND REPRODUCING SOUNDS.

APPLICATION FILED SEPT. 24, 1917.

1,278,042.

Patented Sept. 3, 1918.

UNITED STATES PATENT OFFICE.

MAX SHULMAN, OF NEW YORK, N. Y.

MEANS FOR RECORDING AND REPRODUCING SOUNDS.

1,278,042.

Specification of Letters Patent.

Patented Sept. 3, 1918.

Application filed September 24, 1917. Serial No. 192,944.

To all whom it may concern:

Be it known that I, MAX SHULMAN, a citizen of the United States, residing at New York, in the county and State of New York, have invented a new and useful Means for Recording and Reproducing Sounds, of which the following is a specification.

My invention consists in the novel features hereinafter described.

The objects of my improvement are:

First: To provide a means for recording and reproducing sounds, which may be readily attached to the cabinets of standard sound reproducing machines.

Second: To improve the sundry details of said means for recording and reproducing sounds.

Third: To provide a ready means for producing records of sound, which may be employed for educational and other purposes.

Fourth: To have said means simple, durable and inexpensive.

I attain these objects by the mechanism and sundry parts thereof, illustrated in the drawings, or by any mechanical equivalent or obvious modification of the same.

In the drawings Figure 1 is a sectional elevation on the line A—B of Fig. 2 of my means for recording and reproducing sounds, shown as connected to the cabinet of a standard machine.

Fig. 2 is a plan thereof.

Fig. 3 is a plan of my recording card.

Fig. 4 is a cross-section of my recording card on the line C—D of Fig. 4.

Similar characters refer to similar parts throughout the several views: 11 is the cabinet of a standard sound reproducing machine; 12 is the top cover thereof; 13 is the inverted horn of the machine, which carries on its upper end the hollow arm 15, connected thereto by means of the swivel 14. 16 is the pivot of the swinging hollow arm 15, and 17 is a bracket supporting the upper end of said pivot 16.

Said hollow arm 15 terminates in the goose neck 36, to the inner end 41 of which I propose to connect the recording and reproducing sound box 39.

The card 48 is placed on the turn-table 18, which is provided with the hub 19, which is higher than usual, in order to cause the top or upper surface of the turn table to clear the vertical driving shaft of the standard machine.

The turn table 18 has mounted thereon the Z-bar guides 49, which serve as holders for the card 48, and which impart thereto a positive rotary motion.

Said Z-bars 49 may be secured to said turn table 18 in any suitable manner.

Said card 48 is shown in Figs. 3 and 4 as containing coupling plate 50, which plate 50 may be positively secured to said card 65 by rivets or in any other suitable manner.

Said metal plate 50 serves for positively connecting said card 48 to the coupling 46 at the lower end of the flexible shaft 45 by means of the tapered pins 47 extending from 70 the lower face of said coupling 46, which pins are adapted to fit the openings or sockets 47^a in said plate 50.

Said flexible shaft 45 serves to transmit the motion from said card 48 to the worm 75 43, which is shown as supported by the bracket 42 and meshing with the worm wheel 44.

Said wheel 44 is secured to the horizontal feed screw 24, the two ends of which are 80 shown as supported by the stationary bridge 23 and the standard 20^a.

Said bridge 23 is secured to the rods 22, which serve as guides for the traveling bridge 25, which is operatively connected to 85 said feed screw 24 by means of the detachable feed nut 26^a, which terminates in the controlling lever 26, by means of which said nut 26^a, which consists of only one half of a nut, may be put into and out of contact 90 with said feed screw 24.

Said guide rods 22 are connected at their ends to the standards 20 and 20^a, which terminate at their lower ends in the bases 21, which rest on the top cover 12 of the 95 cabinet 11.

Said traveling bridge 25 is shown as carrying the vertical pin 27, which engages the slotted arm 28, which forms the extension of the rider 29, pivotally connected to the bracket 30 by means of the pin 30^a and the spring clamp 35. Said bracket 30 is shown as secured to said hollow arm 15 by means of the straps 31 and 32, which extend on the underside of said hollow arm 15. 105

Each of said straps 31 and 32 is shown as pivotally connected to said bracket 30 on one side thereof and locked thereto on the other side by means of the strap bolts 52. It is evident that the action of said pin 27 110 on said slotted arm 28 will cause said hollow arm 15 to swing around its pivot 16 as an

axis, and that the motion of said arm 15 will be reduced by said worm 43 and wheel 44 from the rotary motion of the card 48, thereby producing an efficient means for reducing the sounds.

The direction of the threads of the feed screw 24 may be made such as to cause said arm 15 to swing toward the center of the card for recording sounds.

10 Said bracket 30 is shown in Fig. 1 as having an extension 33, which reaches over the swivel 34 of the goose neck 36; and the inner end 41 of the goose neck 36 is shown as connected to said rider 29 by means of 15 the link 37 and pin 38; 38^a is a sleeve or filler-ring shown in Fig. 2 as placed on said pin 38 between said rider 29 and the link 37. The sound box 39 may be connected directly to the traveling bridge 25 instead 20 of to the swiveling arm 15.

Many other changes could be made in the design and details of my means for recording and reproducing sounds without departing from the main scope of my invention.

25 I do not therefore restrict myself to the form of the details as shown; but I intend to include also all mechanical equivalents and reasonably obvious modifications of the same.

30 What I claim as my invention and desire to secure by Letters Patent is:

1. A means for recording and reproducing sounds adapted to be detachably mounted on the cabinet inclosing the spring motor 35 and vertical shaft of a standard sound reproducing machine, said means comprising a sound box and stylus, a turntable adapted to be attached to said shaft and to have its upper surface extend above the end of said 40 shaft, a pair of parallel Z-bar guides secured to said turntable on the upper surface thereof and adapted to rotate therewith, said Z-bar guides having their upper flanges extending inwardly, a recording card having two parallel edges adapted to fit between said Z-bar guides and under said up-

per flanges, thereby being adapted to be readily inserted in position on said turntable and to receive a positive motion from said Z-bar guides, and a means for transmitting positive motion from said card to said sound box.

2. A means for recording and reproducing sounds adapted to be detachably mounted on the cabinet inclosing the spring motor 55 and vertical shaft of a standard sound reproducing machine, said means comprising a sound box and stylus, a recording card, a turntable adapted to be attached to said shaft and to have its upper surface extend 60 above the end of said shaft, thereby being adapted to receive said card on said surface, a means for transmitting positive motion from said turntable to said card, a metal plate secured to said card at the center thereof, a revolving member having at one end thereof a coupling adapted to be detachably connected to said plate, and a means for operatively connecting the other end of said member to said sound box.

3. In a means for recording and reproducing sounds adapted to be detachably mounted on the cabinet inclosing the spring motor and vertical shaft of a standard sound reproducing machine, a sound box and 70 stylus, a recording card, a turntable adapted to be attached to the shaft of said cabinet and to have its upper surface extend above the end of said shaft, thereby being adapted to receive said card on said surface, a means 75 for transmitting positive motion from said turntable to said card, a metal plate secured to said card at the center thereof, said plate having multiple openings, a revolving member, a means for operatively connecting one 80 end of said member to said sound box, a coupling at the other end of said member, and multiple pins in said coupling adapted to fit said openings, thereby detachably connecting said member to said plate.

MAX SHULMAN.
